(57) **CLAIM**

The ornamental design for a reclamer, as shown and described.

DESCRIPTION

FIG. 1 is a front, top, left perspective view of a reclamer showing the new design;

FIG. 2 is a rear, top, right perspective view thereof;

FIG. 3 is a front elevation view thereof;

FIG. 4 is a rear elevation view thereof;

FIG. 5 is a left side view thereof;

FIG. 6 is a right side view thereof; and,

FIG. 7 is a top plan view thereof.

The bottom view of the reclamer is not visible during ordinary use and forms no part of the claimed design. The broken lines of even length shown in the drawings illustrate portions of the reclamer that form no part of the claimed design.

1 Claim, 7 Drawing Sheets
